Peter Clark, Attorney, Chas.

Setters Patent

A Preliminary Description of the Setters Patent and Making part of the Same
containing a description in the words of the said Peter Clark himself of
the Improvement to the Corn Planter and grain Cultivator

I do all this in the present shall Corn Be it known that Peter Clark of
Utica, One County and State of New York have invented a new and
useful Improvement to the Cultivator for agricultural purposes and that
the following is a full and exact Description of the Construction and operation
of the said Machine as invented or improved by me.

The frame of the Cultivator
consists of three bars of wood of suitable dimensions the central one projecting
forward of the side bars and having firmly riveted to its opposite sides two bars
made flat of iron about about twelve inches from its fore end which extends lat-
erally far enough to receive the ends of the side bars which are secured by bolts or
nails. Moreover a to permit them to turn upon them as the Cultivator is expanded
or contracted. The expansion of the Cultivator is regulated by two, three or four
wires which turn at their outer ends upon bolts passing through Circular Metal
cutting the side bars near their their centers into which the wires are inserted
the wires and being halved together by a groove in a wedge cut horizontally
through the central bar and are fastened at different points along the bar by means
of an iron pin. The corner handles are fastened at the fore end by bolts passing down
through four transverse plates of iron and extending backwards and upwards and
downwards by the means of two chains resting on the central bar. The teeth might
best be kept in position and to a front line the cutting ^{rate} per area or surface or area
with a sharp edge along the corner. The two adjacent sides or bars are mostly
parallel angular to each other and turned laterally the teeth also being gradually
increasing from the point towards the shoulder.

On the back side is worn by a deep
groove in the side of the iron work to leave the shoulder and edge black cutting the

190

neck or tusk of the tooth is nearly round having a segment cut from the back
side by a sharp anterior plane and a small rough on the convex side, as is
evident and adds more firmly to the surface of the hole into which it is inserted.
So far it is all secured by a stone so projecting forward underneath the bar and
by two other triangular shoulders pointing backward and laterally nearly at right
angles to each other and also by an iron or wooden wedge being driven down on
the back side of the tusk of the tooth a peg being inserted through a hole near the
top of the tusk on the upper side of the bar. The Cultivator has the common chisel
on the face and by which its cutting may be regulated by means of wedges or India
stones made in the same. and it may have four or five teeth one inserted near
the far end of the Central bar and the others opposite and equidistant along the
side bars and may be used in cultivating all kinds of grain crops, potatoes, to
raise Cotton and the Sugar Cane. The implement looks like a scythe. Con-
sidering the peculiar form of the tooth without a flange the mode of fastening it
and giving it a forward direction suited to the grain and width of the bar - and the
method of graduating the same.
